UNITED STATES PATENT OFFICE.

FELIX EBERHART, OF NEWARK, NEW JERSEY, ASSIGNOR TO AMERICAN CAN COMPANY, OF NEW YORK, N. Y., A CORPORATION OF NEW JERSEY.

SHEET-STACK-HANDLING MECHANISM.

1,152,403.

Specification of Letters Patent.

Patented Sept. 7, 1915.

Application filed November 6, 1911. Serial No. 658,702.

To all whom it may concern:

Be it known that I, FELIX EBERHART, a citizen of the United States, residing in Newark, in the county of Essex and State of New Jersey, have invented a new and useful Improvement in Sheet-Stack-Handling Mechanism, of which the following is a specification.

This invention relates to improvements in sheet stack handling mechanism.

My invention is adapted to handle sheets of material of all kinds, such as paper, cardboard, metal or other substances which are adapted to be piled in stacks, and fed one sheet at a time from the stack to the mechanism for operating on the sheets, such, for instance, as printing, coating, slitting, punching or other mechanisms. But I have shown my mechanism as used in handling metallic sheets, such as tin, used extensively in the manufacture of cans or other articles.

In manufacturing plants, methods and devices for the saving of labor and time are continually sought for, and it is the object of my invention to provide a mechanism which will save one handling of a stack or pile of sheets, and thus reduce the labor and time, as compared with the methods now commonly used, and further to provide a mechanism which will keep the stack or pile of sheets true and prevent the displacement of the sheets in the stack relatively to each other caused by removing the stack from one support to another. In handling

sheets of tin, for instance, where they are fed to a cutting or slitting machine, it has heretofore been customary to place or stack the sheets on an ordinary truck as they come from the coating or lacquering machine, or as the sheets are uncrated in the stock room, then take the truck to the cutting machine, lift the stack of sheets from the truck and place it either on the feed platform of the slitting machine or on an adjacent table or support and subsequently move the stack from this adjacent support to the feeder platform. And often it is impossible to handle the entire stack of sheets at one operation on account of the great weight, and therefore the sheets will invariably become displaced and out of alignment with each other, which necessitates greater care and more time on the part of the operator to feed the sheets correctly into the cutters or slitters. By this method, the stack or pile

of sheets is handled one or more times and sometimes in sections while transferring the pack from the stock room or the coating machine to the cutting machine, and necessarily results in much loss of time and unnecessary amount of labor.

The object of my invention is to provide a feeding mechanism which will do away with the unnecessary handling of the stack or pile of sheets whereby the stack as it is placed on a truck either in the stock room or at the coating machine, remains in place on the platform or table of the truck, and while on said platform and without being disturbed, is transferred with said platform or table to the feeding device, where the platform or table becomes the feeding table for the feeding device or lifting mechanism, and the sheets are then fed by hand from the stack to the cutting and slitting or other mechanism, one sheet at a time, thus saving a great deal of labor and insuring that the sheets have not been displaced out of alignment.

The essential features of my invention, therefore, consist in providing a sheet stack or pile holding platform or table which is adapted to act either as a truck top or platform or as a feeder platform in a sheet feeding and lifting mechanism and a truck and feeding mechanism or lifting mechanism co-operating with this removable, interchangeable and double functioning platform or table.

More specifically, my invention consists in a platform carrying member in the form of a truck adapted to support a platform or table which is slidably mounted on the truck and detachable therefrom, said truck and platform having interengaging members to prevent the accidental displacement of the platform from the truck; a frame having slideable and vertically adjustable main platform or table supporting members mounted therein, said main supporting members being adapted to be lowered to a position below the level of the stack holding platform when mounted on the truck, said vertically adjustable supports being adapted to engage the underside of the platform or table, the supports and the platform forming the feed table of the feeding or lifting mechanism; temporary or auxiliary platform supporting members on the frame onto which the platform is adapted to

be moved from the truck and supported thereby until engaged by the main platform supporting members; adjustable means for automatically raising the main platform 5 supporting members step by step approximately the thickness of a sheet at a time; and sheet centering and guiding members on the platform.

My invention further consists in the parts 10 and devices and in the combinations of the parts and devices herein shown and described or claimed.

In the drawings forming a part of this specification, Figure 1 is a side view, showing 15 my improved mechanism for handling stacks of sheets. Fig. 2 is a vertical, longitudinal section, taken substantially on the line 2—2 of Fig. 3. Fig. 3 is a transverse, vertical section, taken on the line 3—3 of 20 Fig. 1, showing, however, the interchangeable stack supporting platform or table mounted on the auxiliary or temporary supports in the lifting frame. Fig. 4 is a vertical, transverse section of the truck 25 member, taken on the line 4—4 of Fig. 1. Fig. 5 is a plan view of the interchangeable stack supporting platform.

In the drawings, 10 represents any suitable means for transporting a stack or 30 pile of sheets, and preferably is in the form of a truck, having a frame 11, rear wheels 12 and a front wheel 13 mounted in a swivel shaft 14, said shaft 14 having pivoted thereto a handle 15 by which the truck 35 is adapted to be moved about, said handle 15 having preferably rear lugs 16, adapted to engage lugs 17 on the swivel shaft 14 to prevent the shaft 15 from dragging on the floor. The transporting device or truck 40 10 is provided with a horizontal bed portion 18, and is preferably provided on each side thereof with grooves 19 in which are mounted a series of antifriction rollers 20, the tops of said rollers 20 being slightly below 45 the edges forming the grooves 19, whereby to guide the ribs 21 on the stack supporting member or platform or table 22.

The stack supporting platform 22 is preferably provided with a pair of ribs 21, one 50 on either side thereof, and is furthermore provided on one side with an adjustable stack truing or guiding member 23, said member 23 being adjustable on the platform 22 as by means of bolts 24, adapted to be positioned in a plurality of holes 25 in the platform 22, and in order to provide for adjustments between the holes 25, the member 23 is provided with a slot 26 in which the bolt 24 slides. The member 23 is preferably 55 in the form of a casting, having two spaced uprights 27. The table 22 is furthermore preferably provided with additional stack truing or guiding means in the form of a plate 28, which is adapted to be placed 60 on either side of the platform or table 22,

as by means of rods 29 attached to the plate 28 and adapted to be inserted in holes 30 provided in the table 22. The table 22, when being positioned upon the supporting member or bed 18 of the truck is guided by 70 the ribs 21 in the slots 19, and in order to retain the platform 22 after the same has been properly placed on the truck and while the truck is being moved about, I provide a locking member, preferably in the form of a pin 31 mounted in the bed member 18 and approximately centrally thereof and normally projected above the bed 18 as by 75 means of a spring 32 and adapted to engage a socket or hole 33 in the stack supporting table 22. To release the platform or table 22, the pin 31 is adapted to be depressed by means of a hand operated lever 34 pivoted in depending lugs 35 on the underneath portion of the bed 18 and adapted to engage collars 36 rigidly mounted on the pin 31. I have shown my platform 22 as adapted to be slid over the truck from the rear thereof, but it is obvious that changes 80 well within the scope of my invention may 85 be made, whereby the platform or table 22 may be removed from the side of my truck.

The truck or transporting device 10 is adapted to be positioned adjacent the stack lifting and feeding member proper, denoted 90 generally by the reference 37. The stack lifting or sheet feeding mechanism 37 consists of spaced stationary upright frames 38, adapted to be adjustably mounted on suitable bases 39, as by means of gears 40 adapted to be rotated by a hand operated ratchet and pawl mechanism 41, said gears 40 engaging stationary racks 42 on the bases 39. By means of this adjusting mechanism for 95 the frame members 38, the entire frame may 100 be moved inwardly or outwardly relatively to the mechanism adapted to operate on the sheets such, for instance, as a cutting or slitting mechanism. To properly retain the frames 38 in their adjusted position, I 105 preferably provide clamping T-bolts 43 and set screws 44. Rigidly attached to the uprights 38 are temporary or auxiliary supporting members for the platform or table 110 22, said auxiliary supporting members being preferably in the form of a plurality of rollers 45, the tops of said rollers 45 being in the same plane as the tops of the rollers 20 of the transporting member 10, whereby the platform or table 22 slides directly from the rollers 20 onto the rollers 45. The truck 10, as clearly shown in Fig. 2, is 115 adapted to be positioned adjacent the frames 38, and the rear portion of the bed 18 adjacent one of the rollers 45. Mounted in the 120 uprights or standards 38 are vertically movable platform supporting members 46, each having a horizontal ledge 147 and connected by a transverse member 148. These members 46 are adjusted as by means of screws 125 130

47, engaging correspondingly threaded sleeves 48 of the members 46, and these members 46 are furthermore adapted to be lowered to a position below the level of the top 5 surfaces of the rollers 45 so that the members 46 are beneath the table or platform 22 when the platform is slid onto the rollers 45. After the table 22 has been placed upon the rollers 45, the members 46 are then moved 10 vertically upward and engage the table 22 and lift the same in accordance with the feeding movements of the members 46. The screws 47 which feed or raise and lower the members 46 are rotated as by means of bevel 15 gears 49 at their lower ends, said gears 49 being rotated by corresponding bevel gears 50 mounted on a cross shaft 51 adapted to be rotated step by step as by means of a pawl 52 mounted on the lever 53, said lever 53 20 forming one arm of a bell crank having a hub loosely mounted on the shaft 51, the other arm of the bell crank 54 having pivotally connected thereto a link 55 adapted to be reciprocated as by means of an adjustable crank pin 56 mounted on a shaft of the mechanism 57 adapted to operate on the sheets. The pawl 52 is connected to the lever 53 as by means of a spring 154, and it will be apparent that upon each reciprocation 25 of the link or rod 55, the pawl 52 will engage the ratchet gear 155 keyed to the shaft 51 and rotate the shaft 51 step by step. By adjusting the crank pin 56 relatively to the center of the shaft on which said pin is 30 mounted, the amount of oscillation of the pawl 52 may be varied, and is adjusted so as to feed the table supporting members 46 a distance approximately equal to the thickness of each of the sheets being handled. 35

40 In order to throw the pawl 52 to an inoperative position, I provide a foot treadle 58, adapted to engage a vertically reciprocating rod 59, said rod 59 engaging the pawl 52 to lift the same from contact with the ratchet gear 155, and said foot treadle 58 is adapted to be locked in its depressed position as by means of a pivoted lever 60 having a notch 61 thereon engaging the foot treadle 58. I also provide means whereby the shaft 51 45 may be operated by hand to quickly raise the main platform supporting members 46, said means consisting in a lever 62 also loosely mounted on the shaft 51, and having pivoted thereon a pawl 63 connected by a spring 64 to the lever 62, said pawl 63 being normally held out of engagement with the gear 155 by means of a stationary projection 65, adapted to engage a projection 66 on the pawl 63 when said lever 62 is retained in its inoperative position, as by means of a latch 67, pivoted to one of the stationary members 38 and engaging a pin 68 on the lever 62. To lower the main platform members 46, I employ a 50 sprocket gear 69, rotatable as by means of a handle 70 and operating a chain 71 engag- 55

ing a sprocket gear 72 on the shaft 51. With the mechanism which I have provided, the stack or pile of sheets 73, having once been properly placed on the table or platform 22 while the platform is mounted on the bed of the truck, is transferred bodily to the lifting device without the necessity of the stack having to be lifted or without disturbing the relation of the sheets relatively to each other, and as the stack is then fed upwardly step by step the thickness of the sheets, the operator feeds the sheets one at a time from the top of the stack into the cutting or slitting machine 57, and furthermore by the use of the guides 23 and 28 mounted on the table 22, is relieved of the necessity of positioning the sheets before passing them into the machine for operating upon them. 70

75 It is apparent that many changes and variations may be made in the various details of my improved mechanism, and that other forms of transporting devices may be substituted for the three wheel truck which I have shown, and obviously many changes may be made in the platform lifting mechanism without departing from the spirit of the invention, and all such changes and variations are contemplated as fall within the scope of the appended claims. 80

85 I claim:—

1. In a machine of the kind described, a stationary frame, auxiliary platform supporting members thereon, main platform supporting members, said last named members being adjustable above and below the level of the auxiliary supporting members, means for automatically raising the main platform supporting members step by step the thickness of a sheet, a device for rendering said means inoperative and hand operated mechanism for lowering the main supporting platform members, substantially as specified. 90

95

1. In a machine of the kind described, a stationary frame, auxiliary platform supporting members thereon, main platform supporting members, said last named members being adjustable above and below the level of the auxiliary supporting members, means for automatically raising the main platform supporting members step by step the thickness of a sheet, a device for rendering said means inoperative and hand operated mechanism for lowering the main supporting platform members, substantially as specified. 100

2. In a device of the class described, a stationary frame having auxiliary table supporting means, said means comprising spaced rollers, main table supporting means comprising horizontal members vertically adjustable and adapted to be automatically raised step by step, means for automatically raising said main platform members step by step, mechanism for rendering said last named means inoperative and hand operated mechanism for raising said main table supporting members, substantially as specified. 105

3. In a device of the class described, a stack holding and supporting platform or table adapted to be interchangeably supported on a transporting device and a stationary stack lifting mechanism, said platform having two sets of stack guiding or truing members mounted thereon, substantially as specified. 110

4. In a device of the class described, a stack holding and supporting platform or 115

120

125

130

table adapted to be interchangeably supported on a transporting device and a stationary stack lifting mechanism, said platform having two sets of stack guiding or 5 truing members mounted thereon, one of said guiding members being adjustable, substantially as specified.

5. In a device of the class described, a transporting device comprising a horizontal 10 bed portion, a truck supporting the same, and a table having two upright stack guiding members thereon, one of said members being mounted on said table and adjustable in horizontal directions relative to a stack of 15 sheets and parallel with the guiding face of the other member, substantially as specified.

6. In a device of the class described, a transporting device comprising a horizontal bed portion, a table or platform removably 20 mounted thereon, and means for preventing the platform from accidentally sliding off the transporting device, said means comprising a vertical pin slidably mounted in the bed portion and adapted to engage a recess 25 in the platform, substantially as specified.

7. In a device of the class described, a transporting device comprising a horizontal bed portion, a table or platform removably 30 mounted thereon, and means for preventing the platform from accidentally sliding off the transporting device, said means comprising a vertical pin slidably mounted in the bed portion and adapted to engage a recess in the platform, said pin being normally 35 spring pressed into said recess, substantially as specified.

8. In a device of the class described, a transporting device comprising a horizontal bed portion, a table or platform removably 40 mounted thereon, and means for preventing the platform from accidentally sliding off the transporting device, said means comprising a vertical pin slidably mounted in the bed portion and adapted to engage a recess 45 in the platform, said pin being normally

spring pressed into said recess, and a lever pivoted to the bed portion and engaging the pin and adapted to depress the same against the action of the spring, substantially as specified.

9. In a device of the class described, a truck comprising a horizontal bed portion, 50 said bed portion being grooved and having mounted in said grooves anti-friction rollers, and a table or platform removably mounted on said truck, the sides of said grooves serving as guides to properly position the platform as the same is placed upon the truck, substantially as specified.

10. In a device of the class described, a truck comprising a horizontal bed portion, 60 said bed portion being grooved and having mounted in said grooves anti-friction rollers, and a table or platform removably mounted on said truck, the sides of said grooves serving as guides to properly position the platform as the same is placed upon the truck, 65 and a spring pressed pin mounted on the truck and adapted to engage the platform to lock the same in position, substantially as 70 specified.

11. In a device of the class described, a truck comprising a horizontal bed portion, 75 said bed portion being provided with parallel spaced grooves, said grooves having a plurality of rollers mounted therein, the tops of said rollers being below the level of the top of the bed and a table removably mounted on said bed, said table having ribs adapted to slide on the rollers and guided 80 in said grooves, a locking pin mounted on the truck and normally spring pressed into engagement with a recess in the platform, and means for releasing said locking pin, substantially as specified.

FELIX EBERHART.
